Patented July 23, 1974

232,160

COMBINED PACKAGING AND DISPLAY CONTAINER FOR AUTOMOTIVE ROCKER ARMS

Robert G. Gibson, North Palm Beach, Fla., assignor to
Crane Cams Incorporated, Hallandale, Fla.

Filed June 21, 1972, Ser. No. 264,946

Term of patent 14 years

Int. Cl. D9—03

U.S. Cl. D9—185

FIG. 1 is a top perspective view of a combined packaging and display container for automotive rocker arms showing my new design; and

FIG. 2 is a bottom perspective view thereof.

I claim:

The ornamental design for a combined packaging and display container for automotive rocker arms, as shown.
